UNITED STATES PATENT OFFICE.

OSKER W. ELLIOTT, OF CALERA, OKLAHOMA.

DRAFT PRODUCER.

Application filed December 29, 1923. Serial No. 683,448.

To all whom it may concern:

Be it known that I, OSKER W. ELLIOTT, a citizen of the United States, residing at Calera, in the county of Bryan and State of Oklahoma, have invented new and useful Improvements in Draft Producers, of which the following is a specification.

This invention relates to auxiliaries for smoke stacks, chimneys and the like and has 10 for its object the provision of a draft producing device which may be built into the chimney during the construction thereof or which may be manufactured as an attachment thereto, the purpose of the device being 15 to create a draft through the smoke stack or chimney for insuring a hot fire, the device being particularly useful in connection with heating plants which are defective in the draft feature and being of manifest advantage when starting a new fire.

An important object is the provision of a device of this character which is provided with a control damper by means of which the artificial draft may be controlled or cut 25 off entirely.

An additional object is the provision of a device of this character which will be simple and inexpensive to manufacture, easy to install and operate, efficient and durable in 30 service and a general improvement in the art.

With the above and other objects and advantages in view the invention consists in the details of construction to be herein after 35 more fully described and claimed and illustrated in the accompanying drawings, in which:

Figure 1 is a sectional view through a smoke stack equipped with my device showing 40 it of the built in type,

Figure 2 is an elevation and

Figure 3 is a side elevation showing the device constructed as an attachment.

Referring more particularly to the drawings the letter A represents a smoke stack of any ordinary or preferred type leading front a furnace or stove of a heating or power system. In carrying out one form of my invention I provide a section 10 interposed in the 50 smoke stack A and provided at one side with a blower fan casing 11 formed centrally with an air inlet opening 12 and provided with a substantially tangentially arranged outlet conduit 13 which merges into the wall of the 55 section 10 and which communicates with the interior of the section through an opening

14. Suitable braces 15 are provided for holding the blower casing stationary with respect to the smoke stack.

Extending transversely of the casing at 60 opposite sides thereof are angle bars 16 which support bearings 17 for a shaft 18 carrying fan blades 19 of any ordinary or preferred type. For effecting rotation of this shaft, it might be provided with a 65 crank, though I have illustrated it as equipped with a pulley 20 by means of which power may be applied for operating the fan.

Rotatably mounted transversely of the opening 14 is a damper plate 21 having a 70 control arm 22 which is connected to a rod 23 or the like which may be moved for controlling the position of the damper plate.

In the operation it will be seen that when the fan is operated, and the damper plate 75 21 is in open position as shown by full lines in Figure 1, a blast of air will be forced upwardly through the smoke stack from the conduit 13, this blast producing a draft 80 through the smoke stack which will assist the fire. By partly closing the damper plate, it is apparent that the blast and consequently the draft may be cut down and that by closing the damper plate entirely 85 the draft will be cut off even though the fan should still be in operation.

In Figure 3 I have illustrated a slight modification in which I construct the device as an attachment to a smoke stack. In this form the fan casing 24 is formed integral with a conduit member 25 provided with side flanges 26 adapted to be secured at opposite sides of an opening in the smoke stack A by means of suitable bolts 27. At the upper and lower ends of the smoke stack 90 engaging portion of this conduit member are split or sectional bands 28 which embrace the stack and which are clamped thereon by means of bolts 29. I also provide a sectional band 30 mounted below the others 100 and clamped upon the stack by bolts 31. Connected with this band 30 is a brace 32 secured to the fan casing 24. In other respects this form is identical in construction with the first described form and operates 105 in exactly the same manner.

From the foregoing description and a study of the drawings it will be apparent that I have thus provided a simply constructed, inexpensive and easily installed 110 and operated device by means of which a suitable draft may be quickly and easily

produced. As the parts are so few it is apparent that there is very little to get out of order so that the device should have a long and satisfactory life.

5 While I have shown and described the preferred embodiment of my invention it is of course to be understood that I reserve the right to make such changes in the form, construction and arrangement of parts as will not depart from the spirit of the invention or the scope of the subjoined claim.

Having thus described my invention I claim:

15 In combination with a smoke stack, a draft producing mechanism comprising a casing of cylindrical form located exteriorly

of the smoke stack and having an upwardly and laterally inclined extension connected with the stack and communicating therewith, a movably mounted damper within 20 said extension, a pair of bars located at opposite sides of the casing and arranged at right angles to the longitudinal axis of the stack, bearing on said bars, a shaft journaled through said bearings and carrying 25 a rotary lower wheel or fan within the casing, the fan being located in a plane coincident with the longitudinal axis of the stack.

In testimony whereof I affix my signature.

OSKER W. ELLIOTT.
